(57) **CLAIM**

The ornamental design for a chair, as shown and described.

DESCRIPTION

FIG. 1 is a perspective view of the chair showing my new design.

FIG. 2 is a rear elevation thereof.

FIG. 3 is a front elevation thereof.

FIGS. 4 and 5 are side elevation views thereof.

FIG. 6 is a top plan view thereof; and,

FIG. 7 is a bottom plan view thereof.

The fragmented cross-hatching shown on the seat and backrest member is understood to represent fabric and would be continuous throughout the circumscribed area.
